STENCH WARNING DEVICE

John W. G. Jones, Ely, Minn., assignor to Oliver
Iron Mining Company, a corporation of Minne-
sota

Application July 9, 1946, Serial No. 682,175

7 Claims. (Cl. 116—114)

1

This invention relates to warning devices and more particularly to stench warning devices such as are used in underground mines and other places where workmen are confined within restricted spaces which may extend over wide areas and at different elevations and thus make personal warnings extremely difficult, if not impossible.

When there occurs a disaster of one kind or another (for example, fire, flood, noxious gases, etc.) it is, of course, necessary to abandon the installation as rapidly as possible. In underground mines in particular, the workmen are scattered over a very wide area, possibly over several square miles, and at different elevations; and should abandonment of the mine be necessary there is insufficient time to personally warn each workman.

Various warning methods for such installations have heretofore been proposed, but so far as I am aware all of them embody some undesirable characteristics. Of these prior art methods, the one which at present appears to possess the greatest possibilities is that which includes the release of a stench, or exceptionally disagreeable odor. The stench may be injected into the ventilating system, or it may be injected into the piping of the compressed air system with which some mines are equipped (for the operation of the mining tools, etc.). The transportation of the stench through the ventilating system or through the compressed air system would enable it to reach numerous, and possibly all, portions of an underground mine; but such methods of transporting the atomized stench necessitate too long a time for the warning to be effective to all concerned. But proper efficiency may be achieved if the stench is atomized and rapidly released into the atmosphere at numerous points throughout the underground mine or other installation.

According to the teachings of the present invention the installation (such as an underground mine) may be provided with numerous suitably disposed portable units through which the stench may be released and atomized either through the medium of the available compressed air (if there be such) or through a self-contained source of power.

It is accordingly among the objects of the present invention to provide a highly efficient warning device of the type referred to immediately hereinbefore.

Another object is the provision of a unitary device of the class described which may be

2

actuated by remote control as well as at the point of installation.

Still another object is the attainment of the foregoing by a combination of elements which, while highly efficient in operation, is simple and inexpensive to manufacture, install, operate and maintain.

The invention, then, comprises the features hereinafter described and as particularly pointed out in the claims, the following description and the annexed drawings setting forth in detail certain illustrative embodiments of the invention, these being indicative of several of the number of ways in which the principles of the invention may be employed.

In said drawings:

Figure 1 is an elevation, partly in section, of the apparatus of the invention;

Figure 2 is a view on the line II—II of Figure 1; and

Figure 3 is an enlarged sectional elevation of a fusible connection through which the apparatus is operated.

Referring more particularly to the drawings, the numeral 2 designates a vertically disposed cylinder of metal or other suitable material which is easily portable and readily adaptable for attachment to a mine post or other convenient object. The cylinder 2 is provided with an intermediate air-tight partition 3 which forms a lower compartment and an upper compartment, for purposes which will appear hereinafter.

Referring more particularly to Figure 1, the bottom of the vertically disposed cylinder 2 carries a pipe flange 5 which is adapted to cooperate with a detachable closure plate 6, the latter being secured to the pipe flange 5 in any suitable manner. An air-tight seal between the detachable closure plate 6 and the pipe flange 5 is obtained by the use of an intermediately disposed gasket 7. The detachable closure plate 6 is provided with a central opening which communicates with the pipe 9, the latter communicating with a conventional atomizer which as such forms no part of the present invention and is accordingly neither illustrated in the drawings nor further described herein.

Secured to the upper surface of the detachable closure plate 6 is a unitary metallic cage 10 which comprises a plurality of short vertical uprights, a horizontal metal screen platform and a superposed collar. This unitary metallic cage 10 is constructed and arranged to firmly support a sealed container X of ethyl mercaptan or other volatile stench. It is contemplated that the ethyl

mercaptan or other stench will be furnished in a typical sealed glass bottle and accordingly there is provided at the top of the lower compartment of the metallic cylinder 2 a thick pad 11 of cork or other resilient material for cushioning the top of the said bottle.

The upper compartment of the vertically disposed cylinder 2 is provided in the central portion of its head, or top closure, with a central aperture which communicates with a nipple 13 and such other pipe fittings as may be necessary to permit charging the said upper compartment with compressed air or other suitable gas under pressure. That is, the nipple 13 may comprise a type of valve which will permit the introduction of gas under pressure through a simple automobile tire pump, or similar hand pump. On the other hand, the nipple 13 may take the form of a fitting for communication with the compressed air service, etc., if such is available. In any case, the construction of the upper compartment of the cylinder 2 is such as to retain gas under suitable pressures for considerable periods of time, and in order to ascertain the pressure of the gas within the said compartment, there may be provided a conventional pressure gage (not shown).

Adjacent its lower end, the side wall of the upper compartment of the cylinder 2 is apertured to communicate with a short section of pipe 14, the latter carrying a quick-opening valve 16 for the rapid release of the compressed air or other gas within the said upper compartment. The quick-opening valve 16 is entirely conventional and may take the form of the well known disk type of construction (not shown) which is so designed that pressure (within the upper compartment of the cylinder 2) will actually assist in the opening of the valve.

Referring more particularly to Figure 2, the valve 16 comprises a valve stem 17 which extends vertically and is sectionalized, the adjoining sections providing a scarfed joint which is secured by a cotter pin 18. A metallic plate forms a horizontal platform 19 having a center of sufficient size to receive the bonnet of the valve 16 and to permit the said plate to rest on the valve body. At the exhaust side of the valve 16 a pipe 21 extends therefrom, and pipe clamps 22 grip the pipes 21 and 14 to secure the horizontal platform 19 in position. The horizontal platform 19 extends laterally from the valve 16 at either side, as shown in Figure 2. On the upper surface of one overhanging side of the platform 19 there is supported a vertically extending post 24 carrying at its upper end a pivotally attached crossbar 26. In the center of the crossbar 26 there is an aperture which receives, and pivotally holds, the upper end of the sectionalized valve stem 17. Surrounding the valve stem 17 is a coil spring 28, the bottom of which seats against the body of the valve 16, with the top of the said spring seating against the bottom of the crossbar 26. The purpose of this coil spring is to assist in the rapid opening of the valve 16.

Between the outer end of the crossbar 26 and the underlying portion of the horizontal platform 19 there extends a sectional link 30. The upper end of the sectional link 30 extends through and projects beyond the crossbar and carries a right angularly extending pin 34 on which a cam 36 is pivotally mounted. The opposite end of the sectional link 30 extends through, and projects beyond, the horizontal platform 19 and carries an adjustably disposed wing nut 37.

Intermediate its ends the sectional link 30 is constructed and arranged to provide a fusible link which is adapted for rapid disconnection to permit the quick-opening valve 16 to function. 5 More specifically, the intermediate portion of the sectional link comprises two connected brass sections 38 which are shaped to provide a stepped joint. As shown in Figure 3, the stepped joint between the two connected brass sections 38 is 10 soldered with Woods metal and surrounded with a thin sheet of mica insulation 39. Surrounding the thin sheet of mica insulation 39 is a coil 40 of light resistance wire, and surrounding the latter is an outer sheet of thin mica insulation 41. 15 A thin brass case 42 covers the whole fusible link assembly; and a pair of wires 43 connect the ends of the coil 40 with a suitable source of electric current (not shown).

Referring particularly to Figure 1, the numeral 20 50 designates a horizontally disposed cylinder having an end 52 of reduced diameter which screw-threadedly engages an opening in the lower side wall of the lower compartment of the cylinder 2 and is centrally bored to communicate therewith. The diameter of the main bore of the cylinder 50 is substantially larger than that of its reduced end 52 and within it there is disposed a piston 53 having a piston rod 54, the outer end of which is pointed and adapted to 25 extend through the reduced end 52 of the cylinder 50 and substantially into the lower end of the lower compartment of the vertically disposed cylinder 2 when the said piston assumes the dotted line position indicated in Figure 1. However, the piston 53 is biased into the solid line position shown by means of a coiled spring 55, and when in such position the pointed piston rod 54 is withdrawn from the lower compartment of the vertically disposed cylinder 2. The end of 30 the horizontally disposed cylinder 50 which is opposite the screw-threaded end 52 of reduced diameter is closed by means of a screw cap 57 having a central opening which carries in screw-threaded engagement a pipe nipple 58 which extends into the bore of the cylinder 50 to serve as a stop for the piston 53 when it is in its extreme right hand position, as shown in full lines. 35 This pipe nipple 58 is connected by means of suitable piping 59 to the pipe 21 which connects with the exhaust side of the quick-opening valve 16.

As shown most clearly in Figure 1, the side wall of the horizontally disposed cylinder 50 has a vertically extending opening to which there is 40 screw-threadedly connected a pipe 62 which connects with an aperture in the upper portion of the lower compartment of the vertically disposed cylinder 2.

When the piston 53 (in the horizontally disposed cylinder 50) is in the dotted line position there will be communication between the upper portion of the lower compartment of the vertically disposed cylinder 2 and the exhaust side of the quick-opening valve 16.

45 The lower end of the side wall of the lower compartment of the vertically disposed cylinder 2 is provided with an enlarged portion or bushing 65 at a position which is opposite the piston rod 54. This bushing carries in screw-threaded engagement a valve stem 66, the inner end of which is sharpened and adapted to extend substantially into the adjacent lower compartment. The outer end of the valve stem 66 carries a hand wheel 67 for permitting the easy manual movement of the 50 said valve stem to its extreme positions.

In operation:

The cam 36 on the outer end of the crossrod 26 is set to its maximum setting and the wing nut 31 on the lower end of the sectional link 30 is adjusted until the quick-opening valve 16 is in its tightly closed position.

A sealed bottle X of suitable stench, such as ethyl mercaptan, is introduced into the lower compartment of the vertically disposed cylinder 2 through the agency of the removable air-tight closure plate 6 and its superposed bottle-supporting cage 10.

After the insertion of the bottle X into the cage 10 and the replacement of the closure plate 6, the neck of the bottle engages the pad 11 which immediately underlies the partition plate 3.

The upper compartment of the cylinder 2 is charged with a suitable gas and this may be accomplished either by attaching the nipple 13 at the top of the said cylinder 2 to a compressed air line or by utilizing a hand pump or similar instrumentality.

When there is gas in the upper compartment of the vertically disposed cylinder 2 the cam 36 on the outer end of the crossbar 26 may be tripped to open the quick-opening valve 16, allowing gas under pressure to flow through the piping 59, and against the outer end of the piston 53 in the horizontally disposed cylinder 50. The sudden pressure of the gas against the piston 53 will force the piston rod 54 through the reduced end 52 of the cylinder 50 and into the lower compartment of the cylinder 2; whereupon its sharpened extremity will break the side wall of the container X, thereby permitting the ethyl mercaptan, or other liquid stench, to flow out and downwardly through the screen floor of the metal cage 10. The gas pressure against the outer end of the piston 53 will force it to so compress the coiled spring 55 and assume the dotted line position shown in Figure 1, whereupon gas will be permitted to flow from the pipe nipple 58 and through the pipe 62. This by-passing of the gas into the top of the lower compartment of the vertically disposed cylinder 2 results in such a pressure within the said compartment as will force the liquid stench out through the closure plate 6 and into the atomizer (not shown) from which it will be dispensed into the atmosphere.

In the event of failure of the horizontally disposed cylinder 50 and its associated instrumentality, the container X may be broken by the simple expedient of manually screwing in the valve stem 66.

In operating the device by remote control, electric current is applied to the wires 43 which connect the opposite ends of the light resistance coil 40 whereby the Woods metal is melted to open the stepped joint of the fusible link, whereupon the coil spring 23 will quickly open the valve 16.

It will be understood that the teachings of the invention contemplate the use of the units hereinbefore described in suitable number and disposition throughout the installation; and that the same may if desired be operated singly or in various stages of unison.

While I have shown and described certain specific embodiments of the present invention, it will be readily understood by those skilled in the art that I do not wish to be limited exactly thereto, since various modifications may be made without departing from the scope of the invention as defined in the appended claims.

I claim:

1. A warning device comprising a chamber communicating with the atmosphere, a frangible container within said chamber, a stench within said frangible container, a reservoir for maintaining gas under pressure, a cylinder, a piston and piston rod in said cylinder, said piston rod being constructed and arranged to extend into said chamber and puncture said frangible container when the said piston is in its outer position with respect to said cylinder, means connecting said reservoir and said cylinder, a valve in said last-named means, remote control means for actuating said valve, said cylinder having a port which is opened when the said piston is in its outer position, means connecting said port and said chamber, and means tending to maintain said piston in its inner position.
2. A warning device comprising a first chamber communicating with the surrounding atmosphere, a closed container mounted within said first chamber, a volatile odoriferous material confined in said container, a second chamber adapted to confine a compressed gas, means for rupturing said container, means for operating said rupturing means by pressure of gas from within said second chamber, valve means for controlling said operating means, and means connecting said second chamber and said first chamber after operation of said rupturing means for admitting gas to said first chamber and dispersing the odoriferous material.
3. A warning device comprising a first chamber communicating with the surrounding atmosphere, a closed container mounted within said first chamber, a volatile odoriferous material confined in said container, a second chamber adapted to confine a compressed gas, means supported on said first chamber and adapted to be projected thereinto for rupturing said container, means connecting said second chamber with said rupturing means for projecting the latter by pressure of gas from within said second chamber, valve means in said connecting means for controlling operation of said rupturing means, and means connecting said second chamber and said first chamber after operation of said rupturing means for admitting gas to said first chamber and dispersing the odoriferous material.
4. A warning device comprising a first chamber communicating with the surrounding atmosphere, a closed container mounted within said first chamber, a volatile odoriferous material confined in said container, a second chamber adapted to confine a compressed gas, a cylinder supported on said first chamber, a plunger slidably mounted in said cylinder and adapted to be projected into said first chamber for rupturing said container, a pipe connecting said second chamber and said cylinder for admitting gas to said cylinder and projecting said plunger, a valve in said pipe for controlling admittance of gas to said cylinder, and means connecting said second chamber and said first chamber after projection of said plunger for admitting gas to said first chamber and dispersing the odoriferous material.
5. A warning device comprising a first chamber communicating with the surrounding atmosphere, a closed container mounted within said first chamber, a volatile odoriferous material confined in said container, a second chamber adapted to confine a compressed gas, a cylinder supported on said first chamber, a plunger slide-

bly mounted in said cylinder and adapted to be projected into said first chamber for rupturing said container, spring means urging said plunger to retracted position, a pipe connecting said second chamber and said cylinder for admitting gas to said cylinder and projecting said plunger against the action of said spring means, a valve in said pipe for controlling admittance of gas to said cylinder, and a pipe connecting said cylinder and said first chamber, said plunger acting as a valve for interconnecting said second named pipe to said first named pipe after projection of the plunger for admitting gas to said first chamber and dispersing the odoriferous material.

6. A warning device comprising a chamber communicating with the atmosphere, a frangible container within said chamber, a volatile stench within said frangible container, a reservoir for maintaining gas under pressure, pipe means connecting said reservoir and said chamber, a valve in said pipe means and when open establishing communication between said reservoir and said chamber through said pipe means, remote control means for actuating said valve, and means operated by gas from said reservoir for puncturing said container upon actuation of said valve.

7. In a warning device, a first chamber having communication with the atmosphere and adapt-

ed to house a closed container of odoriferous material, a second chamber fixed to said first chamber and adapted to confine a compressed gas, a cylinder fixed on said first chamber, a plunger 5 slidably mounted in said cylinder for projection into said first chamber to rupture the container housed therein, a first pipe connecting said second chamber and said cylinder for admitting gas to said cylinder and projecting said plunger, a 10 valve in said first pipe for controlling admittance of gas to said cylinder, a second pipe connecting said cylinder and said first chamber, and means on said plunger establishing communication between said first pipe and said second pipe when 15 said plunger is projected for admitting gas from said second chamber to said first chamber.

JOHN W. G. JONES.
